UNITED STATES PATENT OFFICE

ARNOLD STUCKI, OF PITTSBURGH, PENNSYLVANIA.

APPARATUS FOR PRESSING PLATE-METAL ARTICLES.

1,033,209.

Specification of Letters Patent.

Patented July 23, 1912.

Application filed May 25, 1908. Serial No. 434,888.

To all whom it may concern:

Be it known that I, ARNOLD STUCKI, a resident of Pittsburgh, in the county of Allegheny and State of Pennsylvania, have invented a new and useful Improvement in Apparatus for Pressing Plate-Metal Articles, of which the following is a specification.

This invention relates to apparatus for 10 pressing, drawing and shaping plate metal.

The object is to provide apparatus for pressing hollow plate metal articles of considerable depth and even of irregular shape, easily, economically and with exactness.

15 This object is accomplished by the construction and arrangement of parts herein-after described and claimed.

In the accompanying drawings Figure 1 is a view showing the matrix or female die 20 in vertical section and the plunger or male die and the holding die in side elevation, showing the parts in the first position; Fig. 2 is a similar view showing the parts at the completion of the operation; Fig. 3 is a 25 plan view of the matrix or female die; Fig. 4 is a vertical section through the same taken at right angles to the sections of Figs. 1 and 2; Fig. 5 is an end elevation of the plunger or male die; Fig. 6 is an inverted plan view of the same; Fig. 7 is a sectional view illustrating the manner of stripping the pressed article from the plunger; and Fig. 8 is a vertical sectional detail illustrating the clamping plate in position to receive 30 a blank.

My improved apparatus comprises three main parts, namely, the matrix or female die 1, the plunger or male die 2, and the clamping or holding die 3, together with 40 suitable holding and clamping means and guides to properly guide the metal to prevent the same from buckling and folding. These parts may be shaped to press plate metal articles of various kinds. The dies 45 shown in the drawings are designed for pressing plate metal railway journal boxes, but this has been selected for illustration only.

The matrix is provided with a die cavity 50 of general rectangular shape having the front wall projecting inwardly near its bot-

tom, as at 6, to form the lip of the journal box, and having below the same the inwardly and downwardly curved portion 7 for forming the front curved face of the box. The 55 side walls of the die are provided with grooves 8 to form corrugations in the side walls of the box and with inwardly projecting ribs 9 to form grooves in the sides of the box for the journal box bolts. 60

The plunger or male die is formed substantially as the complement of the matrix having its front face inclined inwardly, as at 10, to form the lip of the box, and below this having the curved portion 11 for shaping the front curved face of the box. On its side edges it is provided with ribs 12 for pressing the corrugations in the box and with grooves 13 cooperating with the ribs 9 of the matrix for forming the grooves for 70 the journal box bolts. On its lower face this plunger is provided with a rib 14 to form a transverse corrugation in the bottom of the box, said rib being continuous with the side ribs 12. 75

The bottom of the matrix is provided with an opening 15 through which the holding or clamping die 3 projects. The upper end of this die is shaped to form substantially a bottom for the matrix when the dies are 80 in the position shown in Fig. 2, and its upper face is formed as the complement of the bottom face of the plunger or male die 2, being shown as provided with a transverse groove 16 which cooperates with the bottom 85 rib 14 on the plunger to form the transverse corrugation in the bottom of the box.

Obviously these parts may be shaped so as to press articles of different forms.

The plate or blank to be pressed is indicated at 17, Fig. 1, and the finished article is shown in Figs. 2 and 7.

The top face of the matrix is provided at what is termed its front end with a portion 19 slightly higher than its main top face to 90 form a shoulder 20 against which the end of the blank is shoved to position the same. A part of each side wall at the die cavity is cut away so as to obtain a portion of less height, preferably sloping, as indicated at 160 21, and a similar cut away portion 22 is also provided at the rear wall of the die cavity.

Secured to the front end of the matrix is a clamping or holding plate 24 whose inner edge 25 projects into proximity to the front edge of the die cavity, said plate being 5 provided with two side projections or horns 26 projecting at the sides of the die cavity approximately to the cut-away portions 21 in the side walls thereof. This clamping plate is spaced from the main top face of the 10 die by resting on the higher portion 19 and may be adjusted in height by inserting shims between itself and the top face of the die. It is secured to the die by means of bolts or studs 27 projecting up through holes 15 in the plate and provided at their upper ends with means for quickly releasing and clamping said plate. The drawings show for this purpose taper keys 28 driven through slots in the upper ends of the bolts 20 or studs. Obviously, other means, such as winged nuts might be employed. Formed in the body of the matrix are pockets 29 for springs 30 which bear against the lower face of the plate 24 inside of its center of gravity 25 so that when the taper keys 28 are driven back said springs tip the inner edge of said gripping plate upwardly, as shown in Fig. 8, to permit the ready insertion of the blank to be pressed, said blank being slipped in 30 from the back side of the die.

Secured to the sides of the die and projecting over the same substantially to the die cavity are intermediate guides 32 and rear guides 33, these being in the form of 35 bars projecting inwardly and having vertical portions 34 which are secured to the side faces of the matrix by suitable means which permit vertical adjustment, such as bolts 35 projecting through slots 36 in the guides. 40 These guides are spaced from the top face of the matrix a greater distance than the clamping plate 24. A plate can be used, if adjusted loosely enough so that the excess material is allowed to wave or undulate, but 45 not to lap. The rear guides 33 have formed thereon feet 38 which project backwardly and then inwardly around the rear corners of the die cavity, these feet being quite close to the top face of the blank being pressed 50 and serving to hold said blank at the rear corners of the die cavity in the same manner that the plate 24 holds the plate at the front end of the cavity.

The front plate 24 is so connected that it 55 can be moved bodily inwardly toward the die cavity, by providing slots 40 for the holding bolts or studs 27. These slots permit the plate to be shoved inwardly so that its inner edge can act as a stripper to strip 60 the article from the plunger or male die as shown in Fig. 7. For the same purpose the rear wall of the matrix is provided with a hole 41 through which a bar 42 can be inserted to engage the rear edge of the pressed

article and strip the same from the plunger. 65 The matrix is preferably made in two sections divided at its longitudinal center, as indicated by the line 43, in order to permit adjustment to press articles of slightly different widths and to compensate for metal 70 of varying thickness. To enlarge the dies shims are placed between the two sections thereof. The two sections are held together by means of bolts 44 passing through holes in the die. All the dies may be hollow for 75 water cooling if desired.

In the use of the apparatus the plunger or male die 2 is preferably held stationary and the female die or matrix 1 and clamping and holding member 3 are made movable, 80 such as by mounting them on the plungers of suitable hydraulic presses. The matrix and holding die 3 are movable independently.

In using the dies the matrix is brought 85 level with the bottom of the plunger 2, the plate is slipped in from the rear against the shoulder 20 of the off-set portion of the top of the matrix, the sides of the plate contacting with the vertical portions 34 of the intermediate and rear guides. This properly 90 positions the blank and holds the same against shifting. The holding die, or ram, 3 is then brought up and made to clamp the plate tightly between itself and the plunger or male die 2, said parts shaping the plate between themselves, if provided with die faces as shown in the drawings. The matrix or female die is then raised, bending and pulling the metal up over the male die. This 100 causes the plate to take the exact contour of the male die, and it has been found unnecessary to have the extreme bottom portion of the matrix, such as at 7, of the same 105 contour as the outside of the article to be shaped, as this portion of the article is formed by the bending and pulling action over the male die rather than by pressing between the male and female dies. The front 110 gripping plate 24 is in such proximity to the plate that it holds the front edge of the plate down; first, preventing the same from rising and buckling or lapping at the corners of the die cavity; and second, causing the metal to be forced backwardly along the 115 sides of the die cavity. This movement of the metal is facilitated by having the side walls of the die cavity lower than at the front portion. This can be accomplished in various ways, one being by providing the 120 sloping portions 21 of less height which cause the metal to gradually flow in that direction. The intermediate and rear guides 32 and 33 are spaced considerably higher from the top face of the matrix than the front plate so as to permit the edges of the plate to rise and to form slight waves or corrugations and in that way take care of

the surplus metal from the corners. They are, however, so close to the top face of the matrix as to prevent the gathering of the metal to form folds or over-laps. The foot portions 38 of the rear guides are much closer to the top face of the matrix and hold the metal down at the rear corners of the die cavity and prevent it from buckling or lapping, and also cause the superfluous metal 10 to flow inwardly toward the central portion of the rear end of the die cavity, this flowing being facilitated by the cut-away portion 22 in said rear wall. The consequence is that the metal in the edges of the plate is 15 gathered uniformly and distributed over a long distance instead of being all crowded at one or a few points, and without forming folds or laps or leaving superfluous metal at any point. The feet 38 may be separate 20 from and adjustable independently of the rear guides. They have practically the same function at the rear corners of the matrix as the clamping plate at the front corners. The dies have a comparatively long stroke 25 so that the plate is forced into the matrix until the top edge of the article is below the cut-away portions 21 and 22 in the walls of said dies.

The apparatus described is adapted for 30 pressing any plate metal article of considerable depth and of any desired shape. This result is accomplished with ease, exactness and economy; with ease because all lapping, folding, wrinkling and undesired gathering 35 of metal is avoided; with economy, because the pressing is done at one stroke; with exactness, because the plate is prevented from shifting during operation and laps and folds are avoided so that the metal flows and is 40 distributed uniformly each time. This is accomplished by only two power cylinders or forcing mechanisms, one for elevating the clamping or holding ram, and the other for lifting the matrix or female die. It is obvious, of course, that the matrix or even the 45 holding ram may be held stationary, in which case the other dies will have to travel to suit the respective arrangement.

An important feature of the construction 50 is making the walls at the die cavity of different heights in order to assist the clamping plates and guides in crowding the metal away from the corners, preventing the gathering at those points, distributing the 55 surplus metal along a large space and after it gets there, allowing it to undulate uniformly, but not sufficiently to make laps or folds.

With the particular construction shown 60 the main body of the journal box is formed by bending or pulling the metal over the plunger, but the reverse lip is formed by bringing the dies tightly together by the inclined parts 6 and 10 on the matrix and 65 plunger respectively.

What I claim is:

1. Apparatus for drawing and shaping plate metal, comprising a stationary plunger, a matrix movable to strip the metal over said plunger, plate guides and grippers spaced from the upper face of said matrix, and a clamp member movable through the matrix and arranged to clamp the metal against the plunger, said plunger and matrix having complementary shaping 70 faces.

2. Apparatus for drawing and shaping plate metal, comprising a plunger and a non-circular matrix, and a gripping plate above said matrix at the points of abrupt 80 change of the matrix walls and close enough to the face thereof to hold the metal at the points of excess gathering from buckling and force the same to flow to other places to secure a uniform distribution of the metal 85 of the edges of the plate.

3. Apparatus for drawing and shaping plate metal, comprising a plunger and a matrix provided with a die cavity having corners or angles therein and straight sides, 90 and guides positioned above the matrix at the straight sides of the die cavity but not extending continuously around the die cavity and spaced a sufficient distance from the face of the matrix to allow the edges of the 95 plate to undulate and not to lap and thereby securing a gradual and uniform gathering of the metal.

4. Apparatus for drawing and shaping plate metal, comprising a plunger and non-circular matrix, a clamping plate above said matrix and located in such close proximity thereto as to hold the edges of the plate from buckling and force excess metal to other places, and guides also located above 100 the matrix adjacent to said clamping plate and spaced from the matrix face for a greater distance than the clamping plate to allow the edges of the plate to undulate but not to lap, thereby securing a gradual and 110 uniform distribution of the metal of the edges of the plate.

5. Apparatus for drawing and shaping plate metal, comprising a plunger and a matrix provided with a die cavity having 115 angles or corners therein and straight wall portions, said matrix having the walls of its die cavity of lesser height at its straight portions than at its angles to reduce the resistance to the sidewise flow of the metal, 120 and plate guides positioned above the matrix and spaced from the face thereof and not extending entirely around the cavity.

6. Apparatus for drawing and shaping plate metal, comprising a plunger and a non- 125 circular matrix, said matrix having the walls of its die cavity of greater height at the angles than at the straight portions, and a clamping plate above said matrix and located so close thereto at the angles as to hold 130

the edges of the plate from buckling and force the metal toward the portions of the die cavity having low walls.

7. Apparatus for drawing and shaping plate metal, comprising a plunger and a matrix provided with a die cavity having angles or corners therein and straight wall portions and having its walls of greater height at the angles than at the straight portions, guides located above the matrix at the straight portions of the die cavity, and draw plates located above the matrix at the angles.

8. Apparatus for drawing and shaping plate metal, comprising a plunger and a non-circular matrix, said matrix having the walls of its die cavity of different heights at different points, a clamping plate above the higher portion of said matrix walls and positioned so closely thereto as to hold the metal from rising and buckling, so forcing the same toward the lower portions of the die walls, and guides located above said lower portions of the wall and positioned therefrom a greater distance than the clamping plate to permit the edges of the plate to undulate or wave but not to fold or lap.

9. Apparatus for drawing and shaping plate metal, comprising a plunger and a non-circular matrix, said matrix having the walls of its die cavity of greater height at the angles than at the straight portions, and a clamping member above the higher portion of said matrix walls and adjustable with reference thereto and located in such close proximity thereto as to hold the edge of the plate from buckling and forcing the metal thereof toward the lower portions of the die walls.

10. Apparatus for drawing and shaping plate metal, comprising a plunger and a matrix, said matrix having the walls of its die cavity of different heights at different points, a clamping member located above said matrix at the higher portions, and an adjustable guide located above the matrix at the side of the clamping member and at a greater distance therefrom than the clamping plate.

11. Apparatus for drawing and shaping plate metal, comprising a plunger and a matrix, said matrix having the walls of its die cavity of different heights at different points, a clamping plate located above said matrix at the higher portions and adjustable with reference thereto, and a guide located above the matrix at the side of the clamping plate and spaced therefrom a distance greater than the clamping plate.

12. Apparatus for drawing and shaping plate metal, comprising a matrix provided with a die cavity having corners or angles therein and straight wall portions, a co-operating plunger, a gripper or draw plate

located at the angles or corners of the die cavity and spaced from the face of the matrix, and guides also spaced from the face of the matrix at the straight portions of the die cavity.

13. Apparatus for drawing and shaping plate metal, comprising a matrix provided with a die cavity having corners or angles therein, a co-operating plunger, a gripping or drawing plate spaced from the face of the matrix to receive the plate between itself and said matrix face, said gripping plate extending around the corners or angles of the die, and said matrix having the walls of its die cavity beyond said holding plate lower than underneath said holding plate.

14. Apparatus for drawing and shaping plate metal, comprising a matrix provided with a die cavity having corners or angles therein, a co-operating plunger, a gripping or drawing plate spaced from the face of the matrix to receive the plate between itself and said matrix face, said gripping plate extending around the corners or angles of the die, said matrix having the walls of its die cavity beyond said holding plate on a lower layer than underneath said holding plate, and guides above said lower wall portions to prevent the plate from folding.

15. Apparatus for drawing and shaping plate metal, comprising a plunger and a matrix, the matrix having a cavity of general rectangular shape, a holding plate at the angles or corners of the die cavity and spaced from the top face of said die, the walls of the die cavity of said matrix beyond said holding plate being lower than underneath said holding plate.

16. Apparatus for drawing and shaping plate metal, comprising a plunger and a matrix, the matrix having a cavity of general rectangular shape, a holding plate at the corners of the die cavity and spaced from the top face of said die, the walls of the said die cavity of said matrix beyond said holding plate being lower than underneath said holding plate, and guides above said lower portions of the cavity walls.

17. Apparatus for drawing and shaping plate metal, comprising a plunger and a matrix, and a gripping plate applied to the top face of said matrix and spaced therefrom, said gripping plate being mounted to move inwardly and act as a stripper.

18. Apparatus for drawing and shaping plate metal, comprising a matrix, a plunger arranged to enter the same, a gripping plate applied to the top face of the matrix at the side of the die cavity and spaced from the face of said matrix, springs for lifting said plate, means for locking said plate, and a draw plate also arranged above the matrix and spaced from the surface thereof.

19. Apparatus for drawing and shaping

plate metal, comprising a matrix, a plunger arranged to enter the same, a gripping plate applied to the top face of the matrix at the side of the die cavity, means securing said plate to said matrix, springs arranged between the matrix and the plate inside of the center of gravity of the plate, whereby when the securing means are released the inner edge of the plate is elevated, and

guides also arranged above the matrix and 10 spaced from the face thereof.

In testimony whereof, I have hereunto set my hand.

ARNOLD STUCKI.
